UNITED STATES PATENT OFFICE.

FRANCES F. PUTNAM, OF RYE, NEW YORK.

PERAMBULATOR.

1,130,763.

Specification of Letters Patent.

Patented Mar. 9, 1915.

Application filed February 11, 1914. Serial No. 817,982.

To all whom it may concern:

Be it known that I, FRANCES FAULKNER PUTNAM, a citizen of the United States, residing at Rye, New York, have invented certain new and useful Improvements in Perambulators, of which the following is a clear, full, and exact description.

This invention relates to a perambulator.

An object of the invention is to produce a perambulator in which an infant can be comfortably carried, but having an arrangement which will enable the principal parts of the perambulator to be folded up and placed within the body of the perambulator, and to construct the body of the perambulator in such a way that it coöperates with the foldable parts and so that it constitutes a hamper or receptacle for the parts of the perambulator and other articles which may be packed within it when it is not in use as a perambulator, or for convenience in moving household effects.

A further object of the invention is to provide an arrangement for conveniently carrying a cover within the perambulator which can be used to envelop the perambulator-body when the perambulator is not in use; this particularly adapts the device for shipment.

Other objects of the invention will appear more fully hereinafter.

My invention consists in the general combination of parts and simplicity of details hereinafter described, all of which contribute to produce an efficient perambulator.

A preferred embodiment of my invention will be particularly described in the following specification, while the broad scope of my invention will be pointed out in the appended claims.

In the drawings, Figure 1 is a vertical section through the body of the perambulator, the frame being shown in elevation and with the adjacent wheels removed; Fig. 2 is a plan of the frame with the wheels and the body of the perambulator removed, the tongue being represented broken away; Fig. 3 is a perspective showing the frame of the perambulator folded up and representing the tongue as disconnected from the frame; Fig. 4 is a perspective of the body of the perambulator; Fig. 5 is a perspective of a cushion which may be used in the bottom of the perambulator-body; Fig. 6 is a perspective showing the hood of the perambulator attached and folded up; Figs. 7 to 10 in-

clusive represent the four wheels of the perambulator detached; Fig. 11 is a front elevation showing the body of the perambulator with its enveloping cover, which adapts the article to be used as a hamper or shipping case; and Fig. 12 is a horizontal section taken on the line 12—12 of Fig. 11, and particularly illustrating the means for fastening the cover.

Referring more particularly to the parts, the frame 14 of the device preferably comprises two transverse bars or bolsters 15 and 16, the former of which is attached preferably rigidly to the forward extremity of a reach 17, the bolster 16 being preferably rigidly attached to the rear portion of the reach. The reach is preferably formed near its middle point with a joint 18, which may comprise an ordinary hinge 19 attached to the underside of the reach, and near the joint the upper side of the reach is preferably provided with means for reinforcing the joint which may consist of a hook 20 co-operating with an eye 21.

The body 22 of the perambulator is preferably of box form and may consist of a wicker or willow basket having this shape. When the body is supported on the frame it is held in position preferably by means of stakes 23 which are attached to the bolsters and to the ends of the reach so as to fold thereupon. This is preferably accomplished simply by means of hinge connections 24 arranged so that when the stakes are upright 90

the ends of the stakes come against the upper surface of the part to which the stake is attached. These stakes engage the side wall of the body and keep the body from shifting about on the frame. If desired the interior of the body may be provided with a strong-back or stiffener which transmits the weight of the infant directly to the bolsters, thereby relieving the hinge 19 of severe strain. Within the body there is 100 preferably provided a cushion 25 upon which the infant may sit or recline. Between the cushion 25 and the bottom 26 of the body I provide a folded cover 27 which may be removed and applied to the body 22 105 as a cover in such a manner as that illustrated in Figs. 11 and 12. Referring to Figs. 11 and 12, this cover comprises a body section 28 and a bonnet section 29. The bonnet section 29 passes across the opening of 110 the body as a box lid and is provided with a plurality of slots 30 through which

shackles 31 project. These shackles 31 form eyes through which a strap 32 can be threaded, said strap being provided with a buckle 33 or other means for tightening it up. The ends of the cover may be provided with suitable grips or handles 34 adapting the article for convenient handling as a hamper or shipping case.

Preferably on the underside of the forward bolster 15 a tongue-fork 35 is attached by means of a suitable pivot or king-bolt 36. This fork 35 is provided with a removable tongue 37 by means of which the perambulator may be hauled about. The rear part of the fork 35 is formed into a forward axle 38. This forward axle and the rear bolster 16 which constitutes the rear axle are provided with studs or arms 39 at their extremities which receive the hubs of the wheels 40 of the perambulator. These wheels are held in place on the axles by means of split pins 41 or any other suitable means.

The body 22 may be provided with a removable hood 42 which preferably consists of a plurality of bows 43 and a flexible covering 44 attached to the bows. The rear edge of the flexible cover is provided with a draw strap or cord 45 which is adapted to be tightened under the rear roll 46 which is formed at the edge of the body, but any suitable means may be provided for securing the hood at this point. The lower extremities of the bows 43 are detachably secured to a suitable plate 47 attached to the side of the body. By removing the bolts 48 the hood may be removed.

The parts of the perambulator embodying my invention may be readily disconnected and folded up and the principal parts thereof may be placed within the body, to which the folded cover 27 may then be applied if desired to facilitate the handling or shipment of the perambulator.

It is understood that the embodiment of the invention set forth above is only one of the many forms or embodiments the invention may take, and I do not wish to be limited in the practice of my invention nor in my claims to the particular embodiment set forth.

What I claim as new is:—

1. A perambulator having a frame with a joint enabling said frame to be folded, said frame comprising bolsters and stakes having

joint connections with said bolsters adapted to fold upon said bolsters and adapted to assume an upright position, and a body removably supported by said frame and adapted to be held thereupon by said stakes. 60

2. A perambulator having a frame comprising a reach with a joint enabling said frame to be folded, said frame comprising bolsters and stakes having joint connections with said bolsters adapted to fold upon said bolsters and adapted to assume an upright position, and a body removably supported by said frame and adapted to be held thereupon by said stakes. 65

3. A perambulator having a frame comprising a reach with a hinge joint enabling said reach to fold, and means for reinforcing said hinge joint, said frame comprising bolsters and stakes having joint connections with said bolsters adapted to fold upon said bolsters and adapted to assume an upright position, and a body removably supported by said frame and adapted to be held thereupon by said stakes. 70

4. A perambulator having a frame comprising a reach with a hinge joint enabling said reach to fold, and means for reinforcing said hinge joint, said frame comprising bolsters and stakes having joint connections with said bolsters adapted to fold upon said bolsters and adapted to assume an upright position, a body removably supported by said frame and adapted to be held thereupon by said stakes, said bolsters being attached respectively to the parts of said reach, wheels 85 removably carried by the rear bolster, an axle pivotally attached to the forward bolster and wheels removably carried by said axle. 90

5. In a perambulator, in combination, a basket-like body, a folding supporting frame removable from said body and comprising a hinge-jointed reach and a transverse bar or bolster on each section of said reach, the parts of which frame are of such proportions that they may be folded up in said body, and removable wheels for said bolsters having a diameter less than the width of said body. 95

Signed at Rye, New York this 6th day of February 1914.

FRANCES F. PUTNAM.
